UNITED STATES PATENT OFFICE.

GEORG GEPPERT, OF DRESDEN, GERMANY.

APPARATUS FOR CHANGING SHUTTLES IN LOOMS.

No. 889,452.

Specification of Letters Patent.

Patented June 2, 1908.

Application filed October 18, 1905. Serial No. 283,205.

To all whom it may concern:

Be it known that I, GEORG GEPPERT, a subject of the King of Prussia, and resident of Dresden, Ostra Allee 23, Kingdom of Saxony, German Empire, have invented new and useful Improvements in Apparatus for Automatically Changing Shuttles in Looms, of which the following is a specification.

My present invention relates to an apparatus for mechanically and automatically shifting shuttles in looms and in carrying out the same, I employ a batten, a shuttle box movably mounted on the said batten, a fixed shuttle-box, a shuttle magazine, means for normally holding the movable shuttle-box in its normal position, a drive shaft, a mechanical moving device mounted on the said drive shaft, means for operating the said mechanical moving device and means through which the said mechanical moving device operates to move the said movable shuttle-box on the said batten, as will hereinafter be more particularly described.

In the drawing, Figure 1 is a side elevation illustrating my present invention and showing the batten and parts connected therewith at the end of the return stroke. Fig. 2 is a plan view of the parts shown in Fig. 1, showing the batten and the parts connected therewith near the end of the forward stroke. Fig. 3 is a side elevation illustrating the positions assumed by the various parts while a shuttle is being shifted from the shuttle magazine to the movable shuttle-box. Fig. 4 is a side elevation illustrating the positions of the parts while an empty shuttle is being ejected from the fixed shuttle-box to a chamber adapted to receive the same, and Fig. 5 is a detailed view in elevation illustrating a mechanism for maintaining the means for actuating the movable shuttle-box in operation during the required time for the shifting of the shuttle.

In the drawing, 1 designates a batten on which a shuttle-box 2 is fixed.

3 3 are conducting wires leading respectively from terminals at opposite sides of the shuttle-box 2 to an electro-magnet 4, a suitable source of electricity, not illustrated, being included in the circuit to complete the same.

5 designates a pin upon which a lever 6 is pivotally mounted, one end of the lever 6 forming an armature for the electro-magnet 4 and the opposite end of the lever 6 being bifurcated or fork-shaped and adapted to

engage the sleeve 7 of the coupling mounted on a drive shaft 8, by which the loom is operated.

As will be readily understood, a shuttle of ordinary construction when entering the shuttle-box 2 will close the circuit through the electro-magnet 4, actuate the lever 6 against a suitable spring or other means for holding the same in a normal position, whereby the sleeve 7 will be caused to slide a predetermined distance on the drive shaft 8. A cam-disk 9 suitably shaped to perform the functions hereinafter described, is loosely mounted on the said drive shaft 8 and provided with a coupling member adapted to be engaged by a coupling member on the sleeve 7 when the same is shifted on the drive shaft by the movement of the lever 6 when an empty shuttle has entered the shuttle-box 2. 75 A shuttle-box 10 is movably mounted on the batten 1 in any manner known to the art to which this invention relates. At one side and parallel therewith the movable shuttle box 10 is provided with an auxiliary chamber 11 adapted to receive an empty shuttle from the fixed shuttle-box 2 and from which auxiliary chamber 11 the empty shuttle may be readily removed.

12 designates a roller suitably mounted in a frame 13 connected to the movable shuttle-box 10 in such a position that the said roller 12 will be engaged by the periphery of the cam disk 9 when the latter is actuated by being coupled to the drive shaft 8. On the side of the movable shuttle-box 10 opposite the auxiliary chamber 11, I prefer to employ arms 14 adapted when the movable shuttle-box 10 is shifted to its extreme forward position on the batten, to engage the levers 16 adapted to remove the lowermost shuttle from the shuttle magazine 15.

The front wall or member 18 of the movable shuttle-box 10 is pivotally mounted and I employ a cord or chain 17 fixed at one end to a point on the batten, passing over a suitable roll or pulley and secured at the other end to the said front member 18 of the movable shuttle-box, so that when the said movable shuttle-box is shifted to its forward position on the batten, the said front member 18 will be raised in order to permit the lowermost shuttle as ejected from the shuttle magazine, to enter the movable shuttle-box 10, it being understood of course that in the return of the said movable shuttle-box, the front member 18

thereof will drop by gravity and the said movable shuttle-box is normally maintained in its normal position on the batten 1 by means of a pair of springs 19, each extending 5 between the same and the said frame member 13.

20 is a sleeve slidably mounted on the drive shaft 8 and engaged by one end of the lever 21, the opposite end of which is 10 adapted to be engaged by a segment 22 secured to the cam disk 9, and in order to insure the cam disk 9 stopping in the desired or predetermined position, I may provide the segment 22 with a notch 23 into 15 which the free end of the lever 21 is adapted to enter.

In the operation of the hereinbefore described mechanism, the shuttle in the movable shuttle-box 10 becoming empty, is 20 ejected into the fixed shuttle-box 2 whereupon the circuit to the electro-magnet 4 is closed, the magnet excited, the lever 6 actuated to operate the coupling and connect the cam disk 9 with the drive shaft 8, the 25 cam disk 9 being revolved, engages the roller 12 and shifts the movable shuttle-box from its normal position to its forward position in the batten 1. In this forward position the pairs of arms 14 operate the levers 30 16 to eject a filled shuttle from the shuttle magazine 15 into the movable shuttle-box 10, the front member of which is raised through suitable means in the shifting of the shuttle-box on the batten.

35 It will be understood that the shape of the cam-disk 9 will not only be such as to effect the desired movement of the movable shuttle-box on the batten but also after this desired movement of the shuttle-box has 40 been effected, to maintain the movable shuttle-box on the batten, so that while the shuttle which has entered the fixed shuttle-box 2 is being ejected therefrom to the auxiliary chamber 11, the relative movements 45 of the movable shuttle-box and the batten are the same; that is to say,—while the empty shuttle is being shifted from the fixed shuttle-box to the auxiliary chamber, the movable shuttle-box and the batten move 50 together in unison. Of course after the empty shuttle has been removed from the fixed shuttle-box, the circuit to the electro-magnet core is broken and the clutch would normally be released, but in order to maintain 55 the uniform movement of the movable shuttle-box and the batten, the clutch members are maintained in their engagement by means of the sleeve 20, lever 21 and segment 22 on the cam disk 9, until the cam disk has 60 completed a revolution, at which time the free end of the lever 21 drops into the notch 23 in the segment 22, and thereby releases the clutch members, stops the cam disk 9 and permits the springs 19 to return the 65 movable shuttle-box 10 to its normal posi-

tion in order that the weaving process may continue.

I claim as my invention.

1. In an apparatus for automatically changing shuttles in looms, the combination 70 with a batten, of a shuttle box movably mounted on said batten, a fixed shuttle box, means for normally holding said movable shuttle box in its initial position on said batten, a shuttle magazine, means for shifting said movable shuttle box from its initial 75 to its forward position on said batten to effect a transfer of a shuttle from the magazine to the movable shuttle box, and means operative upon a shuttle entering the fixed 80 shuttle box for actuating the last aforesaid means.

2. In an apparatus for automatically changing shuttles in looms, the combination 85 with a batten, of a shuttle box movably mounted on the said batten, a fixed shuttle box, means for normally holding the movable shuttle box in its normal position, a drive shaft, a mechanical moving device loosely mounted on said drive shaft, means for coupling the said mechanical moving device to the drive shaft, means for actuating the last aforesaid means, means through which the said mechanical moving device operates to shift the said movable shuttle box on the 90 said batten, and means for passing a fresh shuttle to the movable shuttle box, substantially as described.

3. In an apparatus for automatically changing shuttles in looms, the combination 100 with a batten, of a shuttle box movably mounted on the said batten, a fixed shuttle box, springs for normally holding the movable shuttle box in its normal position, a drive shaft, a mechanical moving device 105 loosely mounted on said drive shaft, a coupling for connecting the said mechanical moving device to the said drive shaft, means operative upon an empty shuttle passing into the said fixed shuttle box for actuating 110 the said coupling, means through which the said mechanical moving device operates to move the said movable shuttle box on the said batten, and means for passing a fresh shuttle into the movable shuttle box, substantially as described.

4. In an apparatus for automatically changing shuttles in looms, the combination 120 with a batten, of a shuttle box movably mounted on the said batten, a fixed shuttle box, springs for normally holding said movable shuttle box in its normal position, a shaft, a cam disk loosely mounted on said shaft, means through which the said cam disk operates to move the said movable 125 shuttle box on said batten, and means for passing a fresh shuttle into the movable shuttle box, substantially as described.

5. In an apparatus for automatically changing the shuttles in looms, the combina- 130

tion with a batten, a shuttle box movably mounted on the said batten, a fixed shuttle box, springs for normally holding said movable shuttle box in its normal position, a 5 drive shaft, a cam disk loosely mounted on said drive shaft, means for coupling the said cam disk to the drive shaft, means through which the said cam operates to move the said movable shuttle box on the said batten, and 10 means for passing a fresh shuttle into the movable shuttle box, substantially as described.

6. In an apparatus for automatically changing shuttles in looms, the combination 15 with a batten, of a shuttle box loosely mounted on said batten, a shuttle box fixed on the said batten, a drive shaft, a cam disk loosely mounted on the drive shaft, a coupling for connecting the said cam disk and 20 drive shaft, means for operating the said coupling, means through which the said cam disk operates to move the movable shuttle box on the said batten, and means for passing 25 a fresh shuttle into the movable shuttle box, substantially as described.

7. In an apparatus for automatically changing shuttles in looms, the combination 30 with a batten, of a shuttle box movably mounted on the batten, a shuttle box fixed on the said batten, springs for normally holding 35 the movable shuttle box in its normal position, a cam disk, means for actuating the said cam disk, a frame connected to the said movable shuttle box and through which the said cam disk operates to move the movable shuttle box on the batten, and means for passing 40 a fresh shuttle into the movable shuttle box, substantially as described.

8. In an apparatus for automatically 45 changing shuttles in looms, the combination with a batten, of a shuttle box movably mounted on the said batten, a shuttle box fixed on the said batten, means for normally maintaining the said movable shuttle box in 50 its normal position on the said batten, a drive shaft, a cam disk loosely mounted on the drive shaft, a coupling for connecting and disconnecting the said cam disk and drive shaft, means operative upon a shuttle enter- 55 ing the fixed shuttle box for actuating the said coupling to connect the said cam disk and drive shaft, means through which the said cam disk operates to move the movable shuttle box on the said batten, and means for passing 60 a fresh shuttle into the movable shuttle box, substantially as described.

9. An apparatus for automatically shifting 65 shuttles in looms, comprising a shuttle magazine, a batten, a shuttle box fixed on the said batten, a shuttle box movable transversely to and on said batten, a frame connected to the said movable shuttle box, a roller carried by said frame, means actuated upon the ejection of the shuttle from the 70 movable shuttle box to the fixed shuttle box, substantially as described.

for engaging the said roller and sliding the said movable shuttle box on said batten, and means actuated upon the batten reaching its extreme forward movement for passing a shuttle from the said shuttle magazine to the 75 said movable shuttle box, substantially as described.

10. An apparatus for automatically shifting shuttles in looms, comprising a shuttle magazine, a batten, a shuttle box fixed on the 80 said batten, a shuttle box movable transversely to and on said batten, a frame connected to the said movable shuttle box, a roller carried by said frame, means actuated upon the ejection of the shuttle from the 85 movable shuttle box to the fixed shuttle box for engaging the said roller and sliding the said movable shuttle box transversely to and on said batten, means actuated upon the batten reaching its extreme forward movement 90 for passing a shuttle from the said shuttle magazine to the said movable shuttle box, and means for returning the slideable shuttle box to its normal position on the batten at a predetermined time, substantially as de- 95 scribed.

11. An apparatus for automatically shifting shuttles in looms, comprising a shuttle magazine, a batten, a shuttle box fixed on the 100 said batten, a shuttle box movable transversely to and on said batten, a frame connected to the said movable shuttle box, a roller carried by the said frame, means for normally maintaining the movable shuttle box in a 105 position of alignment with the said fixed shuttle box, an operating shaft, a cam loosely mounted thereon and adapted to engage the said roller on the frame connected to the movable shuttle box, means actuated upon the ejection of the shuttle from the movable 110 shuttle box to the fixed shuttle box for actuating the said cam to cause the same to engage the said roller and slide the said movable shuttle box transversely to and on the said batten and means actuated upon the 115 batten reaching its extreme forward movement for passing a shuttle from the said shuttle magazine to the said movable shuttle box, substantially as described.

12. An apparatus for automatically shifting 120 shuttles in looms, comprising a shuttle magazine, a batten, a shuttle box fixed on the said batten, a frame connected to the said movable shuttle box, a roller carried by said frame, means for normally maintaining the 125 movable shuttle box in a position of alignment with said fixed shuttle box, an operating shaft, a cam loosely mounted thereon, a clutch for throwing the said cam into engagement, means actuated upon the batten reaching its extreme forward movement for passing a shuttle from the said shuttle magazine to the said movable shuttle box, and means for insuring the engagement of the clutch 130 during the period necessary for the said

transfer of the shuttle, substantially as described.

13. An apparatus for automatically shifting shuttles in looms, comprising a shuttle magazine, a batten, a shuttle box fixed on said batten, a shuttle box movable transversely to and on said batten, springs for normally maintaining the said movable shuttle box in a position of alinement with the said fixed shuttle box, a frame connected to the said movable shuttle box, a roller carried by the said frame, an operating shaft, a cam loosely mounted thereon, and adapted upon being actuated to engage the said roller, a clutch on the said operating shaft adapted to throw the cam into engagement, an electro - magnet, electrical connections between the terminals of said electrical electro magnet and the opposite sides of the said fixed shuttle box, means actuated by the electro-magnet for throwing said clutch when the circuit to the magnet is closed by the ejection of the shuttle from the said movable shuttle box into the said fixed shuttle box, and means actuated when the batten reaches its extreme forward movement for passing a shuttle from the said shuttle magazine to the said movable shuttle box, substantially as described.
14. An apparatus for automatically shifting shuttles in looms, comprising a shuttle magazine, a batten, a shuttle box fixed on said batten, a shuttle box movable transversely to and on said batten, springs for normally maintaining the said movable shuttle box in a position of alinement with the said fixed shuttle box, a frame connected to the said movable shuttle box, a roller carried by the said frame, an operating shaft, a cam loosely mounted thereon, and adapted upon being actuated to engage the said roller, a clutch on the said operating shaft adapted to throw the said cam into engagement, an electro magnet, electrical connections between the terminals of said electro magnet and the opposite sides of the said fixed shuttle box, an armature for said electro magnet adapted upon the closing of the circuit to the magnet to throw the said clutch to actuate the said cam, levers pivotally mounted on the said shuttle magazine, arms connected to the said movable shuttle box and adapted when the said movable shuttle box reaches its extreme forward movement to engage the said levers to eject a shuttle from the said magazine and cause the said shuttle to pass into the movable shuttle box, and means for maintaining the clutch in engagement while the shuttle is being transferred from the magazine to the shuttle box and the movable shuttle box is being returned to its normal position, substantially as described.
15. An apparatus for automatically shifting shuttles in looms, comprising a shuttle-

magazine, a batten, a shuttle-box fixed on the said batten, a shuttle-box movable on said batten, a frame connected to the said movable shuttle-box, a roller carried by said frame, means actuated upon the ejection of the shuttle from the movable shuttle-box to the fixed shuttle-box for engaging the said roller and sliding the said movable shuttle-box on said batten, and means actuated upon the batten reaching its extreme forward movement for passing a shuttle from the said shuttle-magazine to the said movable shuttle-box, substantially as described.

16. An apparatus for automatically shifting shuttles in looms, comprising a shuttle magazine, a batten, a shuttle-box fixed on said batten, a shuttle-box movable on said batten, a frame connected to the said movable shuttle-box, a roller carried by said frame, means actuated upon the ejection of the shuttle from the movable shuttle-box to the fixed shuttle-box for engaging the said roller and sliding the said movable shuttle-box on said batten, means actuated upon the batten reaching its extreme forward movement for passing a shuttle from the said shuttle magazine to the said movable shuttle-box, and means for returning the slideable shuttle-box to its normal position on the batten, at a predetermined time, substantially as described.

17. An apparatus for automatically shifting shuttles in looms, comprising a shuttle magazine, a batten, a shuttle-box fixed on said batten, a shuttle-box movable on said batten, a frame connected to said movable shuttle - box, a roller carried by the said frame, means for normally maintaining the movable shuttle-box in a position of alinement with the said fixed shuttle-box, an operating shaft, a cam loosely mounted thereon and adapted to engage the said roller on the frame connected to the movable shuttle-box, means actuated upon the ejection of the shuttle from the movable shuttle-box to the fixed shuttle-box for actuating the said cam to cause the same to engage the said roller and slide the said movable shuttle-box on the said batten and means actuated upon the batten reaching its extreme forward movement for passing a shuttle from the said shuttle magazine to the said movable shuttle-box, substantially as described.

18. An apparatus for automatically shifting shuttles in looms, comprising a shuttle magazine, a batten, a shuttle-box fixed on said batten, a frame connected to said movable shuttle - box, a roller carried by said frame, means for normally maintaining the movable shuttle-box in a position of alinement with said fixed shuttle-box, an operating shaft, a cam loosely mounted thereon, a clutch for throwing the said cam into engagement, means actuated upon the batten reaching its extreme forward move-

ment for passing a shuttle from the said shuttle magazine to the said movable shuttle-box, and means for insuring the engagement of the clutch during the period necessary for the 5 said transfer of the shuttle, substantially as described.

19. An apparatus for automatically shifting shuttles in looms, comprising a shuttle magazine, a batten, a shuttle-box fixed on 10 said batten, a shuttle-box movable on said batten, springs for normally maintaining the said movable shuttle-box in a position of alinement with the said fixed shuttle-box, a frame connected to the said movable shuttle-box, a roller carried by the said frame an operating shaft, a cam loosely mounted thereon and adapted upon being actuated to engage the said roller, a clutch on the said operating shaft adapted to throw said cam into engagement, an electro-magnet, electrical connections between the terminals of said electro-magnet and the opposite sides of the said fixed shuttle-box, an armature for said electro-magnet adapted upon the closing of the 15 circuit to the magnet to throw the said clutch to actuate the said cam, levers pivotally mounted on the said shuttle-magazine, arms connected to the said movable shuttle-box and adapted when the said movable shuttle- 20 box reaches its extreme forward movement to engage the said levers to eject a shuttle from the said magazine and cause the said shuttle to pass into the movable shuttle-box, and means for maintaining the clutch in engagement while the shuttle is being transferred from the magazine to the shuttle-box and the movable shuttle box is being returned to its normal position, substantially 25 when the batten reaches its extreme forward movement for passing a shuttle from the said 30 shuttle magazine to the said movable shuttle-box, substantially as described.

20. An apparatus for automatically shifting shuttles in looms, comprising a shuttle magazine, a batten, a shuttle-box fixed on 35 said batten, a shuttle-box movable on said

batten, springs for normally maintaining the said movable shuttle-box in a position of alinement with the said fixed shuttle-box, a frame connected to the said movable shuttle- 40 box, a roller carried by the said frame an operating shaft, a cam loosely mounted thereon and adapted upon being actuated to engage the said roller, a clutch on the said operating shaft adapted to throw said cam into engagement, an electro-magnet, electrical connections between the terminals of said electro-magnet and the opposite sides of the said fixed shuttle-box, an armature for said electro-magnet adapted upon the closing of the 45 circuit to the magnet to throw the said clutch to actuate the said cam, levers pivotally mounted on the said shuttle-magazine, arms connected to the said movable shuttle-box and adapted when the said movable shuttle- 50 box reaches its extreme forward movement to engage the said levers to eject a shuttle from the said magazine and cause the said shuttle to pass into the movable shuttle-box, and means for maintaining the clutch in engagement while the shuttle is being transferred from the magazine to the shuttle-box and the movable shuttle box is being returned to its normal position, substantially 55 as described.

60 In witness whereof I have hereunto set my hand in the presence of two witnesses.

GEORG GEPPERT.
